WILLIAM BARDSLEY, OF KEARNEY, NEW JERSEY.

DOOR CHECK AND CLOSER.

1,250,542.

Specification of Letters Patent. Patented Dec. 18, 1917.

Application filed April 29, 1916. Serial No. 94,322.

To all whom it may concern:

Be it known that I, WILLIAM BARDSLEY, a citizen of the United States, and a resident of Kearney, in the county of Hudson and State of New Jersey, have invented certain new and useful Improvements in Door Checks and Closers, of which the following is a specification.

The invention pertains more particularly to door checks and closers of the character embracing a spring for closing the door, jointed lever arms at one end connected therewith and at the other end to an abutment, and means for checking the action of the spring during the closing movement of the door. Ordinarily these door checks and closers have the spring portion applied to the door and the outer end of the lever arms to the lintel over the door or the spring to the rigid door frame and the outer end of the lever arms to the door, as occasion may require. During the opening of the door, the spring is placed under an increased tension, and when the door is released to close, the spring automatically closes the same. Usually the spring is inclosed in a casing having connected with it a checking cylinder containing a valved piston and a checking liquid, the piston being connected with and actuated from a spindle extending through the spring. It has been found desirable also to provide means by which at the closing point of the door, the spring may act with a slightly increased force so as to latch the door, without creating any undue slamming of the door. My invention comprises a casing containing a closing spring, associated lever arms connected therewith and at one end mounted on a spindle which extends through the spring and means for checking the action of the spring during the closing of the door. My invention resides more particularly in the means for checking the action of the spring during the closing of the door and one purpose of the invention is to dispense with the customary liquid checking cylinder and its parts and provide a mechanical friction check as a substitute therefor. The checking means of my invention comprise a friction band connected with the main lever arm and engaging the exterior of the spring inclosing casing, together with accessory features whereby the door may be opened without the application

of undue energy and be promptly closed under a restraint rendering the operation efficient and desirable. The invention also embraces features of detail which will be understood from the description hereinafter presented.

Referring to the accompanying drawings,

Figure 1 is a top view of a combined door closer and check constructed in accordance with and embodying the invention, the same being shown as applied to a door and door frame and the position of the parts when the door is closed being shown by full lines and when the door is opened by dotted lines;

Fig. 2 is a vertical section through the same taken on the dotted line 2—2 of Fig. 1;

Fig. 3 is a detached top view of the main casing for the spring, with the lever arms and checking means detached therefrom;

Fig. 4 is a sectional view through the casing for the spring taken on the dotted line 4—4 of Fig. 2;

Fig. 5 is a vertical section through a portion of the checking mechanism, taken on the dotted line 5—5 of Fig. 1, and

Fig. 6 is a detached sectional view through a portion of the device, taken on the dotted line 6—6 of Fig. 3, Fig. 6 showing more particularly the shunt or cam by which the checking action is partly released at the closing point of the door for the purpose of permitting the spring to effectually close and latch the door.

In the drawings, 10 designates the door, 11 the lintel above the same, 12 the drum or spring casing containing the spring 13, and 14, 15, respectively, the lever arms which are pivotally connected together at their outer ends, the lever 14 being at its inner end mounted on the upper end of a vertical spindle 16 extending centrally of the casing 12, and the outer end of the lever 15 being pivotally secured to a bracket 17 fastened to the lintel 11. The lever 15 is adjustable as to length as usual, and the lever 14 is of special formation in respect to certain features connected with the checking devices, but otherwise is not of unusual formation. The casing 12 is of cylindrical outline and has a bottom 18 which may be integral with securing bracket arms 19 adapted to be fastened to the door 10 in the customary manner. The bottom 18 of the casing is formed with a seat 20 for the lower end of the spindle 16,

- as shown in Fig. 2. The casing 12 is also provided with a cap 21 having a central tubular opening formed by a sleeve 22 and within the sleeve 22 is mounted a sleeve 23 which is provided within the chamber of the casing 12 with a laterally extending arm 24 which is recessed out, as at 25, in its outer end to form a hook 26 and an auxiliary arm or finger 27, as shown more clearly in Fig. 4.
- 5 Within the sleeve 23 is mounted the spindle 16, said spindle being free to rotate or tightly held, as may be preferred, said spindle 16 not being an actuating spindle in the special form of the invention illustrated. The bottom 10 of the casing 12 is formed with lugs 28 (Fig. 4) between which the lower hooked end of the spring 13 is caught, and the upper hooked end of the spring 13 is caught upon the hook 26. The arm 24 is an actuating 15 arm for winding up or increasing the tension of the spring 13 during the opening of the door and controlling the action of the spring during the closing of the door. The sleeve 23 rotates within the sleeve 22 during 20 the opening and closing movements of the door, and said sleeve 23 extends above the body of the cap 21 and at one side of its upper end is flattened, as at 29, and upon this end of the sleeve 23 is placed a toothed 25 wheel 30, whose bore is flattened to engage the flattened side 29 of the sleeve 23, whereby said wheel becomes keyed upon said sleeve and when rotated imparts its motion to the sleeve 23.
- 30 The spindle 16 extends upwardly above the wheel 30 and receives upon its upper end the inner end of the lever arm 14 and above said end a washer 31 and nut 32, the said end of the lever arm 14 being close against the wheel 30 and the washer and nut serving to retain said lever arm in position. The sleeve 23 is provided at its lower portion with a washer 33 and a cross-pin 34, which pin is extended through a hole in the spindle 35 16 and serves as a support for the sleeve.
- 35 Pivottally connected with the lever arm 14 is a double-ended dog 35 which is of customary form and purpose and one point of which engages the wheel 30 when the mechanism is arranged for a right hand door and the other point of which is placed in engagement with said wheel when the mechanism is arranged for a left hand door. I illustrate the wheel 30 as having notches or teeth 40 entirely around its periphery, but it is well known in this art that only a few of the notches are ordinarily made use of, and hence the wheel 30 may have as many of the notches as may be deemed desirable. The dog 35 keys the lever arm 14 to the wheel 30, and it has already been explained that the wheel 30 is keyed to the sleeve 23 whose arm 24 engages the spring 13, and hence it will be obvious that when the lever arm is 45 moved during the opening of the door it will wind the spring 13 and that said spring will unwind during the closing of the door, the lever arm 14 then moving in a reverse direction. When the mechanism is arranged for a right hand door, the dog 35 will have 50 the position shown in Fig. 1 and the hook 26 of the arm 24 will act against the upper end of the spring 13, and when the mechanism is to be arranged for a left hand door, the dog 35 will be swung around so that its 55 other point will engage the wheel 30, and under such condition the finger 27 will be the actuating member to engage the upper end of the spring 13.
- 60 The present invention pertains more particularly to the means provided for checking the action of the spring 13 during the closing movement of the door, and this mechanism comprises, among other features, a brake band 36 preferably of metal and 65 containing a lining of leather or the like 137 and which band is secured at its ends to cast shoes 37 pivotally connected with the ends of a two armed lever 38, one arm 39 of which is longer than the other arm 40. 70 The lever 38 may be said to be a double ended rocking lever, rocking in one direction during the opening of the door and in the other direction during the closing of the door. The lever 38 is pivotally mounted 75 on one end of a rod 41, said lever containing an opening 42 (Fig. 5) to receive the end of said rod and a rivet 43 being employed to pivotally connect said lever and rod. The brake band 36 extends around and 80 engages the drum or casing 12, as shown in Fig. 1, and the ends of the band extend thence to the shoes 37 carried by the lever 38. The rod 41 extends through apertures in arms 44 depending from the lever 14 and 85 at its outer end said rod 41 is internally threaded to receive a screw 45 which extends through an arm 46 depending from the lever arm 14. The screw 45 is provided with a head 47 at the outer side of the arm 46 and said screw is provided as a means 90 for adjusting the rod 41 toward and from the casing 12, this being for the purpose of drawing the lever 38 outwardly or adjusting it inwardly so that the relation of the brake band 36 to the casing 12 may be regulated 95 to meet such conditions as may arise. By adjusting the rod 41 I am permitted to obtain the correct frictional engagement of the brake band with the drum or casing 12 100 and also to compensate for any wear that may take place on the lining of the band. The double armed lever 38 is of special importance in that during the opening of the door and the movement of the lever 14 from 105 the position shown in Fig. 1 by full lines to that indicated by dotted lines, the longer arm of the lever 38 moves inwardly toward and the shorter arm of said lever moves outwardly from the drum or casing 12 with the 110
- 115
- 120
- 125
- 130

result that the band 36 is loosened with respect to its engagement with the drum or casing and the door 10 is opened in opposition to the force of the spring 13 but without any material resistance from the band

36. During the closing of the door the longer arm of the lever 38 moves outwardly from and the short arm of said lever inwardly toward the drum or cylinder 12, and

10 the result of this is that the longer arm of the lever acts to draw the band 36 with great firmness against the drum or casing 12, said drum and band then serving to check the closing action of the door, while still per-

15 mitting the spring 13 to effectually close the door. The brake band has a differential action, said band becoming relaxed in its tension against the drum or casing 12 during the opening of the door and binding against

20 said drum or casing 12 with considerable firmness during the closing of the door. The rod 41 and screw 45 may be utilized to regulate the resistance the band 36 shall exert against the drum during the closing

25 action of the door.

It is desirable that while checking the closing action of the door, the door should, within a short distance, say six inches, from its fully closed position, be somewhat re-

30 leased from the checking medium in order that the spring 13 may be enabled to firmly close and latch the door, and to this end I provide the cap 21 with a shunt or cam plate 48 which projects laterally from the

35 casing and is formed with a slotted arm 49 which extends through a recess 50 cut in the edge of the casing 12 and receives within its slot a lug 51 formed on the cap 21 and is there secured by a screw 52. The shunt or

40 cam plate 48 is adjustable radially by means of its slotted arm and the screw 52 and is prevented from having any rocking motion horizontally by reason of the walls of the recess 50 and the presence of the lug 51.

45 The shunt or cam plate 48 only comes into use during the closing action of the door, since during the opening action of the door the short arm of the lever 38 turns outwardly and the cylinder or casing 12 carries

50 the shunt or cam plate 48 to some considerable distance away from said short arm of the lever 38, as shown by the dotted lines in Fig. 1. After the door has been opened and then released to close, the band 36 dur-

55 ing the movement of the lever arm 14 while the door is closing, is tightened upon the cylinder or casing 12 and said cylinder or casing 12 turning within the band 36 finally, near the closing point of the

60 door, causes the shunt or cam plate 48 to ride against the roller 53 carried by the short arm 40 of the lever 38 and forces said arm outwardly and consequently turns the longer arm of the lever 38 inwardly or

65 toward the drum or casing 12 and this has

the result of relaxing the tension of the band 36 on the drum or casing 12 so that at this time the spring 13 may act with efficient force to compel the complete closing and latching of the door.

70

During the opening of the door therefore the brake band 36 performs no special duty, but during the closing of the door, said band acts by engaging the drum or cylinder 12 to retard or check the movement of the door.

75

Near the closing point of the door, the cam plate or shunt 48 acting against the lever 38 relaxes the tension of the band 36 on the drum or casing 12, and hence at this time the spring 13 is under less restraint

80

and may readily close and latch the door. The amount of pressure the band may exert at the closing point of the door, may be regulated by adjusting the shunt or cam plate 48 radially. An outward adjustment of

85

the shunt or cam plate 48 results in increased loosening of the band 36 on the cylinder or drum 12, and hence less friction or resistance is created, while when the shunt or cam plate is adjusted inwardly, the

90

short arm of the lever is permitted to have a closer relation with the drum or cylinder 12 and the result of this is that the friction of the band 36 on the drum or casing 12 is increased. I therefore regulate the friction

95

the band shall exert at the closing point of the door by the adjustment of the shunt or cam plate 48. The shunt or plate 48 is not on the true arc of a circle, but has a small arc at its middle portion and then curves

100

inwardly on its end portions on a different arc. The fact that the shunt or plate 48 is of cam shape also permits me to regulate the period at which the quick closing ac-

tion of the door shall take place, this quick closing action of the door not taking place until the plate 48 engages the roller 53 and forces the short arm of the lever 38 outwardly.

105

The construction illustrated is shown as arranged for on a right hand door. The same mechanism may be employed for a left hand door, and when it is desired to arrange the mechanism for a left hand door, I loosen one of the screws, say that numbered

110

54, fastening one end of the band 36, and turn the band upside down, the rod 41 permitting this, and then refasten the band by the screw 54, this placing the short arm of the lever 38 at the opposite side of the lever

115

14 to that illustrated in Fig. 1. I also take the plate or shunt 48 from its position shown in Fig. 1 and place it at the opposite side of the cap 21 at the recess 55 provided for it,

and I swing the dog 35 around so that its idle point shown in Fig. 1 is brought into engagement with the wheel 30. The changes just mentioned are all that are required for adapting the mechanism from its condition for a right hand door to a condition suitable

120

125

130

for a left hand door. In order to avoid adjustment I will preferably provide two of the shunt or cam plates 48, one for the recess 50 or for the position shown in Fig. 1, 5 and the other for the recess 55, so that a person desiring to change the mechanism from a right to a left hand door or from a left to a right hand door might not have to make any change so far as the shunt or 10 cam plate is concerned. I preferably provide the short arm of the lever 38 with a roller 53 adapted to the position of the shunt or cam plate 48 for a right hand door and also with a corresponding roller 56 to 15 engage the shunt or cam plate when the brake band is turned upside down for adaptation to a left hand door. When the mechanism is specially constructed for either a right hand door or for a left hand door 20 and not intended to have its parts transposed, only one cam plate or shunt will be made use of and only one roller will be carried by the short arm of the lever 38.

What I claim as my invention and desire 25 to secure by Letters Patent, is:

1. A door closer comprising a cylindrical casing containing a door closing spring, and 30 pivotally connected lever arms, one of which is operatively connected with said spring, combined with checking mechanism comprising a brake band engaging said casing and lever arms connected to the ends of said band and to said one lever arm and adapted on the opening and closing of the door to 35 exert a differential binding of the band on said casing, relaxing said band on the opening of the door and tightening the same on said casing during the closing of the door.

2. A door closer comprising a cylindrical 40 casing containing a door closing spring, and pivotally connected lever arms, one of which is operatively connected with said spring, combined with checking mechanism comprising a brake band engaging said casing, lever arms connected to the ends of said 45 band and to said one lever arm and adapted on the opening and closing of the door to exert a differential binding of the band on said casing, relaxing said band on the opening 50 of the door and tightening the same on said casing during the closing of the door, and means for relaxing said band at the closing point of the door so that the spring may effectively close and latch the door.

3. A door closer comprising a cylindrical 55 casing containing a door closing spring, and pivotally connected lever arms, one of which is operatively connected with said spring, combined with checking mechanism comprising a brake band engaging said casing, and a two-armed lever connected to the ends 60 of said band and pivotally mounted on said one lever arm and adapted on the opening and closing of the door to exert a differential binding of the band on said casing, re-

laxing said band on the opening of the door and tightening the same on said casing during the closing of the door.

4. A door closer comprising a cylindrical casing containing a door closing spring, and 70 pivotally connected lever arms, one of which is operatively connected with said spring, combined with checking mechanism comprising a brake band engaging said casing, a two-armed lever connected to the ends of 75 said band and pivotally mounted on said one lever arm and adapted on the opening and closing of the door to exert a differential binding of the band on said casing, relaxing said band on the opening of the door and 80 tightening the same on said casing during the closing of the door, and a plate carried by said casing for engaging one arm of said two-armed lever at the closing point of the door for forcing the other end of the lever 85 to relax said band, so that the spring may effectively close and latch the door.

5. A door closer comprising a cylindrical casing containing a door closing spring, and 90 pivotally connected lever arms, one of which is operatively connected with said spring, combined with checking mechanism comprising a brake band engaging said casing, a two-armed lever connected to the ends of 95 said band and pivotally mounted on said one lever arm and adapted on the opening and closing of the door to exert a differential binding of the band on said casing, relaxing said band on the opening of the door and tightening the same on the casing during 100 the closing of the door, and means for adjusting said two-armed lever and band with relation to said casing.

6. A door closer comprising a cylindrical casing containing a door closing spring, and 105 pivotally connected lever arms, one of which is operatively connected with said spring, combined with checking mechanism comprising a brake band engaging said casing, a two-armed lever connected to the ends of 110 said band and pivotally mounted on said one lever arm and adapted on the opening and closing of the door to exert a differential binding of the band on said casing, relaxing said band on the opening of the door 115 and tightening the same on said casing during the closing of the door, a roller carried by one arm of said two-armed lever and a plate mounted on said casing for engaging 120 said roller at the closing point of the door for forcing the other arm of the two-armed lever to relax said band, so that the spring may effectively close and latch the door.

7. A door closer comprising a cylindrical casing containing a door closing spring, and 125 pivotally connected lever arms, one of which is operatively connected with said spring, combined with checking mechanism comprising a brake band engaging said casing and a two-armed lever connected to the ends 130

of said band and pivotally mounted on said one lever arm and adapted on the opening and closing of the door to exert a differential binding of the band on said casing, relaxing said band on the opening of the door and tightening the same on said casing during the closing of the door, and a shunt plate adjustably mounted on said casing for engaging one arm of said two-armed lever 10 at the closing point of the door for forcing the other end of the lever to relax said band, so that the spring may effectively close and latch the door.

8. A door having self-closing means, combined with checking mechanism connected to said door and its frame comprising a cylindrical casing, pivotally connected lever arms one of which is pivotally mounted on said casing, a brake band engaging said casing and a pivotally mounted two-armed lever connected at its ends with the ends of said band and one of said arms of said lever being longer than the other, and said lever being pivotally mounted on said lever arm 20 mounted on said casing and carried thereby, whereby said band is caused to exert a differential binding on said casing, the band being relaxed on the opening of the door and tightened on said casing during the 25 closing of the door.

9. A door having self-closing means, combined with checking mechanism connected to said door and its frame comprising a cylindrical casing, pivotally connected lever arms one of which is pivotally mounted on said casing, a brake band engaging said casing and a pivotally mounted two-armed lever connected at its ends with the ends of said band and one of said arms of said lever 30 being longer than the other, and said lever being pivotally mounted on said lever arm mounted on said casing and carried thereby, whereby said band is caused to exert a differential binding on said casing, the band being relaxed on the opening of the door and tightened on said casing during the 35 closing of the door, and means for relaxing said band at the closing point of the door so that the door-closing means may effectively 40 close and latch the door.

10. A door having self-closing means, combined with checking mechanism connected to said door and its frame comprising a cylindrical casing, pivotally connected lever arms one of which is pivotally mounted 45 on said casing, a brake band engaging said casing and a pivotally mounted two-armed lever connected at its ends with the ends of said band and one of said arms of said 50 lever being longer than the other, and said lever being pivotally mounted on said lever arm mounted on said casing and carried

thereby, whereby said band is caused to exert a differential binding on said casing, the band being relaxed on the opening of the 65 door and tightened on said casing during the closing of the door, and means carried by said lever arm mounted on the casing for adjusting the relation of said two-armed lever and said band to said casing.

11. A door having self-closing means, combined with checking mechanism connected to said door and its frame comprising a cylindrical casing, pivotally connected lever arms one of which is pivotally mounted 70 on said casing, a brake band engaging said casing and a pivotally mounted two-armed lever connected at its ends with the ends of said band and one of said arms of said lever being longer than the other, and said lever being pivotally mounted on said lever arm mounted on said casing and carried thereby, whereby said band is caused to exert a differential binding on said casing, the band being relaxed on the opening of the door 75 and tightened on said casing during the closing of the door, and means carried by said lever arm mounted on the casing for adjusting the relation of said two-armed lever and said band to said casing comprising a 80 rod slidably mounted in arms depending from said lever arm and connected with said two-armed lever and an adjusting screw for effecting the movement of said rod.

12. A door having self-closing means, 95 combined with checking mechanism connected to said door and its frame comprising a cylindrical casing, pivotally connected lever arms one of which is pivotally mounted on said casing, a brake band engaging said 100 casing and a pivotally mounted two-armed lever connected at its ends with the ends of said band and one of said arms of said lever being longer than the other, and said lever being pivotally mounted on said lever arm 105 mounted on said casing and carried thereby, whereby said band is caused to exert a differential binding on said casing, the band being relaxed on the opening of the door and tightened on said casing during the closing 110 of the door, and a shunt plate mounted on said casing for engaging the shorter arm of said two-armed lever at the closing point of the door for forcing the other arm of said lever to relax said band, so that the 115 door-closing means may effectively close and latch the door.

Signed at New York city, in the county of New York and State of New York, this 27th day of April, A. D. 1916.

WILLIAM BARDSLEY.
